UNITED STATES PATENT OFFICE.

JOHN J. BAILEY, OF NEW YORK, N. Y.

AMMONIA-GAS COMPRESSOR.

SPECIFICATION forming part of Letters Patent No. 599,487, dated February 22, 1898.

Application filed January 12, 1897. Serial No. 618,942. (No model.)

To all whom it may concern:

Be it known that I, JOHN J. BAILEY, a citizen of the United States, residing at New York, in the county and State of New York, 5 have invented a new and useful Improvement in Ammonia-Gas Compressors, of which the following is a specification.

My present invention is designed as an improvement upon the device described and 10 shown in my application for patent filed August 27, 1896, Serial No. 604,055; and the object of my invention is to more quickly and effectually cool the piston cylinders and valves during the operation of compressing the 15 anhydrous ammonia or other gas and to so construct such valves that their operation will be more positive and certain and more perfectly gas-tight.

In carrying out my invention and in combination with the essential features of my hereinbefore-named application I construct the circular body with channels for cooling liquid that extend between the piston-cylinders, and whose respective ends open into the 25 spaces between the valve-cases and the covers thereto. The cooling-water enters at the bottom of the circular body and flows around through these channels and over the valve-cases in succession and away at the bottom 30 portion, thus keeping the body, the piston-cylinders, and the valves and cases cool with a liberal supply of water. The valves at the outer ends of the piston-cylinders are alike and their construction and operation are hereinafter more particularly described.

In the drawings, Figure 1 is an elevation and partial section illustrating my improved apparatus. Fig. 2 is a cross-section through part of the body of the machine. Fig. 3 is a 40 longitudinal section, in larger size, of the valves and valve-case. Fig. 4 is a plan of the valve-case shown in Fig. 3, and Fig. 5 is a cross-section of one of the valve-case sleeves.

The body A of the machine is approximately circular, and is provided with a central chamber and with four piston-cylinders at right angles to each other. Upon one side of the body the disk a and ring a' constitute the heads, and the head b is at the other side 45 of the body and through it the shaft f passes, the same being provided with a crank f' and crank-pin f². (See dotted lines, Fig. 1.) Two

double yokes g g' are employed and are placed oppositely. To one yoke the pistons e e' are connected and to the other yoke the pistons 55 e² e³ are connected. Each piston, where it passes into the cylinder, is round and fits such cylinder closely. The other portion of the piston is a half-cylinder, and, as seen in the drawings, the flat surfaces of the pistons 60 are toward each other. The two yokes are coupled to opposite pistons in pairs and occupy only a space corresponding in width to the diameter of the circular pistons. A direct and even thrust on the pistons is thus 65 effected and space is economized. The yokes are slotted, as shown, and the ends of the pistons are bolted thereto, so that the pistons are connected in pairs. The crank is provided with a sleeve within a slide-block that 70 is in the slots of the yokes. These parts receive motion from the crank and crank-pin, and the parts just described are similar to parts described in my hereinbefore-named application and operate in like manner and do 75 not require further description.

The circular body A is made with channels d d' d² d³ d⁴, that extend through the body between the piston-cylinders, and the ends open into the respective spaces or chambers 80 between the valve-cases h and their covers h². These channels are preferably rectangular in cross-section.

At the lower part of the circular body A pipes k k' pass through the body into the 85 channels d and d⁴, and between these is a tubular opening 10, communicating with the open center of the body A to convey oil within the body, as in my hereinbefore-named application.

The water to cool the body A, its piston cylinders and valves, and their cases in the 90 operation of the mechanism enters by the pipe k into the channel d and passes therefrom over one valve-case, through the channel d', over another valve-case, through the channel d², over another valve-case, through the channel d³, over another valve-case and into the channel d, and away by the pipe k'. A constant circulation is thus maintained 95 around through the cylindrical body A to cool the same and its valves.

The valve-cases h are each made alike, with two circular chambers opening from the outer

ends into the ports 5 6, and these ports open into the by-passes 3 4 in the body of the machine to convey the ammonia gas. These circular chambers are smaller at the inner ends and larger at the outer ends and the outer ends are threaded.

- The valves $t' t$ seat in opposite directions in the base of the valve-cases h and their stems move in the sleeves $i' i$ and are provided with 10 cross-pins 7, adapted to move in slots in the opposite portions of the sleeves $i' i$. These sleeves $i' i$ are provided with flanges fitting the cylindrical openings in the valve-cases, and the insides of said sleeves are longitudinally grooved, as shown in the cross-section, 15 Fig. 5, to lessen friction in the movement of the valve-stems and to provide oil-channels for lubrication. Rings $n' n$ surround the sleeves between the respective flanges, the 20 ring n being below the cross-pin in the stem of the valve t and the ring n' above the cross-pin in the stem of the valve t' , and I employ helical springs $l' l$, surrounding the sleeves, the spring l being between the ring n and 25 the lower flange of the sleeve i and the spring l' between the ring n' and upper flange of the sleeve i' . The spring l consequently exerts an upward pressure to keep the valve t to its seat and the spring l' a downward pressure to 30 keep the valve t' to its seat, the pressure being exerted at one end of the springs upon the rings $n' n$ and pins 7. The screw-caps $m' m$ fit in the threaded openings of the valve-cases and screw down against packing-rings 35 and against the sleeves $i' i$ to securely hold the same in place and form gas-tight joints. The valve-cases h are secured to the circular body A by tap-bolts 12 and the covers h^2 are secured in place by the tap-bolts 13, as shown 40 in Figs. 1 and 4.

I claim as my invention—

1. In an ammonia-gas compressor, the combination with the pistons, the yokes to which they are coupled, and the shaft and crank 45 for operating the same, of the circular body having cylinders for the pistons and channels that extend around in and through the body between the piston-cylinders and that are rectangular in cross-section and have open 50 ends at opposite sides of the cylinders, and form receptacles for cooling liquid, and covers that extend over the open ends of the channels and make the same continuous, substantially as set forth.
- 55 2. In an ammonia-gas compressor, the com-

bination with the four pistons, the yokes to which they are coupled in pairs and the crank and shaft for operating the same, of the circular body containing the piston-cylinders and having channels that extend around, in 60 and through the body between the piston-cylinders, the valve-cases at the outer ends of the piston-cylinders and the covers to said cases, the said channels opening near the outer ends of the cylinders into the covers to 65 provide connected channels for a circulation of cooling liquid through the body and around the valve-cases, substantially as set forth.

3. In an ammonia-gas compressor, the combination with the body, the cylinders and pistons and means for operating the pistons, of the valve-cases at the outer ends of the piston-cylinders having inlet and exit passages, the valves $t' t$ seated in opposite directions, sleeves in which the stems of said valves are 70 moved, a cross-pin in each valve-stem, and the helical springs acting against said pins and valves to hold the same to their seats, substantially as specified.

4. In an ammonia-gas compressor, the combination with the body, the cylinders and pistons, and means for operating the pistons, of the valve-cases at the outer ends of the piston-cylinders having inlet and exit passages, the valves $t' t$ seated in opposite directions, 75 pins 7 in the valve-stems, sleeves $i' i$ receiving the valve-stems and having flanges and slotted at opposite sides for the pins 7, the rings $n' n$, the helical springs $l' l$ and the screw-caps $m' m$, substantially as set forth. 80

5. In an ammonia-gas compressor, the combination with the body, the cylinders and pistons, and means for operating the pistons, of the valve-cases at the outer ends of the piston-cylinders having inlet and exit passages, 85 the valves $t' t$ seated in opposite directions, pins 7 in the valve-stems, sleeves $i' i$ receiving the valve-stems and having flanges and slotted at opposite sides for the pins 7, and longitudinally grooved internally to reduce 90 the bearing on the valve-stem and provide receptacles for oil, the rings $n' n$, the helical springs $l' l$ and the screw-caps $m' m$, substantially as set forth.

Signed by me this 4th day of January, 1897. 105

JOHN J. BAILEY.
